PERCENTAGE COMPUTATION AID APPARATUS

John R. Sears, Norfolk, Va.

Application January 27, 1947, Serial No. 724,616

13 Claims. (Cl. 235—87)

1

This invention relates to percentage aid computation apparatus, and more particularly to apparatus for co-relatively positioning tables or columns of numerical values in such manner that percentages of principal values at varying percent rates may easily be determined. The invention may be embodied in apparatus of the general class referred to in which percentages are tabulated in columns on rotatable drums or cylinders.

An object of the invention is to provide an apparatus of the character stated which, for a given capacity as to the range of computations, is more compact than apparatus previously provided for the same use. In attaining this object, I provide, in general, two apparatus groups or sections for determining percentages of primary and secondary parts of a principal value, based on a selected percent rate, together with means or markings for co-relating the thus determined percentages and rendering them corelatively readable and distinguishable from percentages of the principal sum based on other and non-selected percent rates.

Another object of the invention is to provide a percentage computation aid apparatus including two coaxial, rotatable cylinders mounted to rotate independently of each other without any tendency of one cylinder to rotate the other cylinder.

Another object of the invention is to provide apparatus of the kind referred to including a simple and effective arrangement for mounting bands or rings marked with percentage values on a cylinder or drum.

Other objects will become apparent from a reading of the following description, the appended claims, and the accompanying drawings, in which:

Figure 1 is a front elevational view of a simple form of apparatus embodying the invention;

Figure 2 is a longitudinal sectional view of the apparatus shown in Figure 1, but with some parts omitted;

Figure 3 is a detail end elevational view of a cylinder and band, illustrating the arrangement for maintaining the band in a predetermined circumferential setting or position on the cylinder;

Figure 4 is a detail view showing a group of alternative percent rate markings which may be used in place of percent rate markings shown in Figure 1;

Figure 5 is a perspective view illustrating a casing or housing for enclosing apparatus of the kind shown in Figures 1 to 4;

Figure 6 is a front elevational view of a modified embodiment of the invention;

2

Figure 7 is a fragmentary vertical section on the line 7—7 of Figure 6; and

Figure 8 is a fragmentary section on the line 8—8 of Figure 7.

Figures 1 to 3 inclusive illustrate a simple and preferred form of apparatus adapted to be used as an aid in computing percentages, particularly for computing interest in banks, building and loan association offices, and other establishments in which interest on different principal amounts and at different interest rates has to be computed as part of the daily work.

The apparatus shown in Figures 1 to 3, considered in its general nature, includes a support or stand A on which are mounted two independently rotatable cylinder member B and B' disposed with their inner ends in face-to-face relationship behind an opaque shield generally designated C fixed to the support A by a bracket 1. The shield C is shown as comprising a single structural part, but considered functionally it comprises two indicating sections, one designated 2 between the vertical center line of the apparatus and the left end of the shield, and the other designated 2' between the vertical center line and the right end of the shield as viewed in Figure 1.

The shield indicating section 2 is formed with a principal value designation part 3 formed with a window 4, and is provided with a series of horizontally aligned percent rate markings 5, 6, 7, 8, 9, and 10. The percent rate markings may be changed according to the computations to be made. The markings shown in Figure 1 are respectively in descending progression 6%, 5½%, 5%, 4½%, 4%, and 3%. The shield indicating section 2' is similar to the indicating section 2 and includes a primary value designation part 3' formed with a window 4', as well as percent rate markings 5', 6', 7', 8', 9', and 10' which are the same as to value and progression as the percent rate markings 5 to 10 inclusive on the section 2.

The cylinder B is provided with an annular column 11 of primary principal value indicia located at the left end of the cylinder so as to be behind the principal value designation part 3 of the shield section 2. The column 11 is marked with principal values increased by 100 units between each two adjacent value indicia up to ten thousand. The cylinder B also is provided with annular columns 12, 13, 14, 15, 16, 17 of primary percentage indicia. These columns are so located on the cylinder B as to be disposed respectively behind the percent rate markings 5, 6, 7, 8, 9, and 10 on the shield section 2. The shield section 2 is formed with a plurality of view openings 18, 19,

20, 21, 22, and 23 arranged in stepped relationship with the respective view openings being disposed directly under, that is aligned transversely with the respective percent rate markings 5, 6, 7, 8, 9, and 10.

The cylinder B can be rotated by means of a knob device 24 attached to the cylinder in a manner to be described hereinafter. By rotating the cylinder, any selected principal value in the column 11 can be made to register with the window 4. The primary percentages listed in the columns 12, 13, 14, 15, 16, and 17 are such that when a selected principal value registers with the opening 4 the correct percentage will be displayed in the view opening directly below the percent rate marking used in the computation. For example, if it is desired to determine the interest on \$8,600 at 6% for one month, the cylinder B is turned until the principal value \$8,600 registers with the window 4, and the percentage or interest displayed through the view opening 13 directly under the 6% marking 5 is seen to be \$43.00. If it is desired to find the interest on \$8,600 for one month at 5½%, the reading of the interest is made through the view opening 19 directly under the 5½% marking 6, and is found to be \$39.42. Similarly, the interest or percentage at the rates shown in the markings 7, 8, 9, and 10 can be read easily through the openings 20, 21, 22, and 23, respectively.

The cylinder B' is provided or marked with an annular column 11' of secondary principal value indicia increasing by ones or units up to \$100. The cylinder B' also is marked or provided with annular columns of percentage indicia designated 12', 13', 14', 15', 16', and 17' disposed respectively behind the percent rate markings 5', 6', 7', 8', 9', and 10'. The shield section 2' is formed with stepped view openings 18', 19', 20', 21', 22', and 23' respectively aligned directly under the percent rate markings 5', 6', 7', 8', 9', and 10'. The view openings in the shield indicating section 2' are arranged in stepped relationship similarly to the view openings in the shield section 2, that is, the uppermost opening 18' in the shield section 2' is aligned horizontally with the uppermost opening 18 in the shield section 2, and both openings 18 and 18' are disposed under the 6% markings. Similarly, the immediately lower openings 19 and 19' are horizontally aligned with each other, and are disposed under the 5½% sign markings, and so on. The percentage columns 12' to 17' inclusive are so constituted that when the cylinder B' has been turned by means of a knob device 24' to bring a selected secondary principal value into registration with the window 4', the percentage sought will be found displayed in the view opening disposed under the marking displaying the percent rate use in the computation. Thus, if it is desired to find the interest on a secondary principal value of \$44 for one month at 6%, the cylinder B' is rotated to bring the value \$44 in the column 11' into registration with the window 4'. The interest will be observed in the view opening 18' aligned with the six percent sign marking 5', and will be seen to be \$0.22.

One of the advantages of a construction embodying the invention and including the two cylinders B and B' in combination with the two shield sections 2 and 2' marked as described above is that the apparatus can be built compactly to occupy a small space and still have the capacity for computing percentages at varying rates on a large number of principal values. Thus, in the

form shown, the cylinders need be of a diameter only great enough to permit the inclusion of one-hundred items in each column, which does not require a cylinder of great circumference, but still permits the finding of percentages on values varying by ones up to ten thousand. For example, in finding the interest on \$8,644, for one month at 6%, the cylinder B would be set to cause the primary principal value \$8,600 to register with the window 4, and the interest on the primary value would be observed through the view opening 18 as being \$43.00. Then the cylinder B' would be positioned to cause the secondary value \$44 to register with the opening 4', and the secondary interest would be observed through the window 18' as being \$0.22. By a simple addition, the interest on the whole sum of \$8,644 would be determined as \$43.22. It is apparent that if the two cylinders B and B' and the associated shield sections were not used in combination, only a single cylinder and shield section being employed, it would be necessary for the columns on the single cylinder to include ten thousand items, requiring a very large circumference and prohibitively large apparatus.

In accordance with a further feature of the invention, the shield C is provided, formed, or marked to facilitate the reading of the related primary and secondary percentages in the proper view openings. In the form shown in Figure 1, the shield C is marked with guide lines 25, 26, 27, 28, 29, and 30 which extend respectively between and denote horizontally aligned pairs of view openings in the respective shield sections 2 and 2'. Thus, the guide line 25 extends between the horizontally aligned view openings 18 and 18', both of which are disposed under the 6% markings; the guide line 26 extends between the view openings 19 and 19' both of which are disposed under the 5½% markings; and so on. In finding both the primary and secondary percentages of a given number, say \$8,644, the cylinders B and B' are positioned as previously explained and the primary percentage—\$43.00—is read through the opening 18 under the 6% marking; but instead of locating the secondary opening 18' by reference to the percent marking 5' above it, the operator's eye follows across the guide line 25, which visually pairs the opening 18' with the opening 18. The guide line 25 serves in a sense to couple the openings 18 and 18' which are associated respectively with the primary and secondary percentages under similar percent rate markings. In the same way, the guide lines 26, 27, 28, 29, and 30 visually couple other associated pairs of view openings so as to facilitate substantially simultaneous reading of related primary and secondary percentages determined at equal percent rates.

In using the apparatus, it is desirable to operate both cylinders from one side, usually the left side, in order that the operator's right hand may be free for making written notes. The apparatus shown in Figures 1 and 2 is so constructed as to provide this advantage and the particular construction is such that it provides the further advantage that turning of either of the cylinders B—B' will not tend to turn the other cylinder and move it from its previous setting. In other words, the arrangement is such that if the cylinder B is first set to cause a selected principal value to be displayed through the window 4, the cylinder B' may be turned thereafter to cause a selected secondary principal value to register with the window 4' without producing any tend-

ency to turn or drag the cylinder **B** from its previously set position. For obtaining these desirable advantages, the cylinders **B** and **B'** are mounted on the support **A** by a novel construction shown in Figure 2. This construction includes a hub **31** which is integral with the support **A** and is bored to receive a sleeve **32**, the opposite ends of which protrude from the hub **31** and provide bearing portions shown at **33** and **33'**. The sleeve may be locked or secured in fixed relationship to the hub **31** by any suitable means, for example, by set screws **34**—**34'**. The cylinders **B** and **B'** are formed with hubs **35** and **35'** journaled respectively on the bearing portions **33** and **33'**, so that the cylinders are mounted independently on the sleeve **32** and do not touch each other. The knob **24** for turning the cylinder **B** is secured to the outer and left hand end of the cylinder **B** by any suitable means, such as screws **36**. The knob **24'** for turning the cylinder **B'** is, as stated before, located at the same side of the apparatus as the knob **24**. In order to connect the knob **24'** with the cylinder **B'** without causing contacting of any parts which would cause one cylinder to tend to follow the other in rotation, the knob **24** is formed with an axial opening **37** into which extends, with ample clearance, a shank **38** on the knob **24'**. The shank **38** is screwed to the left end of a rod **39** which extends through the sleeve **32**, the knob **24'** being locked to the rod **39** by means of a screw **40**. The right end of the rod **39** is attached by a screw **41** to a non-circular part **42** fitted in a similarly shaped recess **43** in the cylinder **B'**.

It will be seen that the group of parts comprising the knob **24'**, the rod **39**, and the cylinder **B'** has no operative or contacting connection with the group of parts comprising the knob **24** and the cylinder **B**. There is positive clearance between the groups of parts, and consequently either knob and the parts connected to it can be turned to rotate the associated cylinder without producing any tendency to rotate the other cylinder.

Preferably, the percent rate markings 5 to 10 inclusive and 5' to 10' inclusive are interchangeable with other percent rate markings, according to the computations to be made. The markings may be changed in any desired manner, as for example, by using replaceable or interchangeable tabs or labels or by writing in different percent rates. Figure 4 shows a set of percent rates which could be substituted for those shown in Figure 1. The percent rates shown in Figure 4 are all based on six percent but they progress according to the number of months for which interest is to be computed.

When a different set or series of percent rate markings is used, it usually will be necessary to change the columns of percentages 12 to 17 inclusive and 12' to 17' inclusive. In order that this change may be made readily, the columns of percentage values preferably are marked on removable rings or bands **44** (see Figure 3) adapted to be slipped on and off the cylinders **B** and **B'** in an axial direction. Similarly replaceable bands or rings **44** marked with different columns of principal values may be employed. The bands **44**, or the cylinders, or both are provided with means for maintaining the bands in predetermined positions circumferentially with respect to the cylinders. In the construction shown in Figure 3, the bands are formed with internal corrugations **45** adapted to mate with similarly formed corrugations **46** on the cylinder **B**. The cylinder **B'** may be formed with similar corrugations adapted to

mate with internal corrugations of the associated bands.

Figures 1 to 4 show a percentage computation aid apparatus of simple form comprising a minimum number of parts. The construction described may easily be mounted in a casing or housing **D** as shown in Figure 5. Only a few reference characters have been applied to Figure 5 to indicate generally parts which correspond to parts of the construction shown in Figures 1 to 4 inclusive.

In order that the cylinders **B** and **B'** may be held against axial shifting on the sleeve **32**, means are provided for coupling the cylinders **15** to the hub **31** of the standard **A**. The hub **35** of the cylinder **B** is formed with a groove **47** adjacent its tapering inner end portion **48**. The groove **47** receives a stud **49** carried by a spring finger **50** secured to the hub **31** by a screw **51**. **20** When the parts are in the assembled relationship shown in Figure 2, the stud **49** cooperates with the sides of the groove **47** to maintain the cylinder **B** against axial shifting. However, the cylinder **B** may be removed by forcing it axially **25** toward the left, which will cause the spring finger **50** to yield, permitting the stud **49** to rise out of the groove **47** and allow the cylinder hub **35** to move axially to the left. When the cylinder **B** is to be set in its operative position, it is placed **30** on the sleeve **32** and pushed to the right, causing the tapered edge **48** to lift the stud **49** against the urge of the spring finger **50**. Upon further movement of the cylinder **B**, the stud **49** will drop into place in the groove **47**. Similarly, the **35** hub **35'** of the cylinder **B'** is formed with a groove **47'** which receives a stud **49'** carried by a spring finger **50'** secured to the hub **31** by a screw **51'**.

Figures 6 to 8 illustrate a modified embodiment **40** of the apparatus including a movably mounted opaque screen **E** adapted to be set in different positions for obstructing or cutting off view through the openings **13** to **23** inclusive and **18'** to **23'** inclusive, with the exception of two selected **45** horizontally aligned view openings related to equal percent rate markings. Broadly considered, the movable screen aids in the reading of primary and secondary percentages in much the same manner as the guide lines **25** to **90** inclusive shown **50** in Figure 1. Consequently, the guide lines may be omitted from the shield **C** in the construction shown in Figures 6 to 8. The shield **C** shown in the modification differs from that shown in Figure 1 also in that it is provided with a slot **52** **55** and an additional bracket **53** for assisting the bracket **1** in supporting the shield on the standard **A**. Otherwise the parts shown in Figures 6 to 8 inclusive, with the exception of the screen **E** and the parts which mount it, are the same **60** as parts shown in Figures 1 to 3 inclusive and are designated by corresponding reference characters.

The screen **E** is shaped to conform to the surface of a cylinder and is mounted concentrically **65** with the cylinders **B** and **B'** and the shield **C**. The screen may be mounted either inside or outside of the shield **C**, since in either case, the screen can obstruct the view of percentage values on the cylinders **B** and **B'**. In the form shown, **70** the screen **E** is disposed between the cylinders **B**—**B'** and the shield **C**, that is, the screen **E** is mounted behind the shield **C**.

The screen is provided with two mounting arms **54** and **55** which merge at inner ends with a flat **75** hub **56** snugly mounted in a slot **57** formed in

the hub 31 of the standard A. The flat hub 56 is journaled on the fixed sleeve 32 and has its opposed flat surfaces crimped or otherwise formed or equipped to provide for frictional engagement of the hub faces with the sides of the slot 51 to hold the screen E frictionally but releasably in set position. The screen E is rockable about the sleeve 32, and in order that it may move high enough, it is formed with a slot 58 through which the shield mounting bracket 53 extends. A button 59, secured to the screen E and extending freely through the slot 52 in the shield C, provides for convenient manual raising and lowering of the screen.

For rendering two selected horizontally aligned view openings in the shield C co-relatively functional, the screen E is formed with two elongated horizontal slots 60 and 60', which in effect constitute a single slot means extending substantially across the screen. When it is desired to determine the percentage of say \$8,644 at six percent for one month, the knobs 24 and 24' are operated to turn the drums B and B' until the primary secondary principal values \$8,600 and \$44 register respectively with the windows 4 and 4' in the shield C. Then the button 59 is moved to rock the screen E to a position in which the slots 60 and 60' are disposed directly under the view openings 18 and 18'. The primary and secondary percentages will then appear respectively in the windows 18 and 18' as \$43.00, and \$0.22. With the screen E positioned as described, the opaque portion of the screen, that is the part of the screen other than the slots 60 and 60', will obstruct view through the openings 19 to 23 and 19' or 23' so that the only percentages viewable through the shield C and screen E are those determined at the 6% rate which are to be found.

If it should be desired to find the percentage or interest on \$8,644 for one month at five and one half percent, the screen is removed downwardly to cause the slots 60 and 60' to register with the view openings 19 and 19', all the other view openings then being cut off or rendered non-functional. By shifting the screen E to other positions, the primary and secondary percentages can readily be determined on the basis of any selected interest rate.

The constructions illustrated by way of example embody the invention in preferred forms but it will be understood that changes may be made without departing from the invention as defined in the claims.

I claim:

1. In a percentage computation aid apparatus, a support; a relatively fixed shield having two indicating sections; a first rotatable member provided with indicia, individual items of which each represents a primary part of a principal value and are adapted to be denoted selectively by one of said indicating sections according to the rotated position of said member; a second rotatable member provided with indicia, individual items of which each represents the secondary part of a principal value and are adapted to be denoted selectively by the other of said indicating sections according to the rotated position of said second member; means mounting said rotatable members on said support independently of each other with their inner ends in mutual face-to-face relationship for rotation about a common axis and with each of said members being free to rotate without tending to rotate the other of said members; a first manually operable device connected to the outer end of one of

5 said members for rotating it; a second manually operable device at the same end of said one of said members; means operatively connecting said second manually operable device to the other of said members for rotating it, said second manually operable device and said connecting means being free of connection to said first manually operable device and said one of said members, whereby either manually operable device may 10 be operated to rotate the member connected thereto without producing any tendency to rotate the other member, and means cooperating with the respective indicating sections of said shield to facilitate the collective relating of selected markings on the two cooperating members.

2. In a percentage computation aid apparatus, a support; a relatively fixed shield having two indicating sections; a first rotatable member provided with indicia, individual items of which each represents a primary part of a principal value and are adapted to be denoted selectively by one of said indicating sections according to the rotated position of said member; a second rotatable member provided with indicia, individual items of which each represents the secondary part of a principal value and are adapted to be denoted selectively by the other of said indicating sections according to the rotated position 15 of said second member; a sleeve carried by said support and having end portions protruding oppositely from said support to provide axially spaced bearing portions on which said members are journaled respectively with their inner ends in face-to-face relationship; a first manually operable device connected to the outer end of one of said members for turning it and having an axial opening coaxial with said sleeve; a rod connected to the outer end of the other of 20 said members and extending through said sleeve and said opening; a second manually operable device on said rod and adjacent said first manually operable device, said second manually operable device, said rod, and the one of said members to which the rod is connected being completely free of connection to said first manually operable device and the member to which it is connected, and means cooperating with the respective indicating sections of said shield to facilitate the collective relating of selected markings on the two cooperating members.

3. In a percentage computation aid apparatus, a support; a relatively fixed shield having two indicating sections; a first rotatable member provided with indicia, individual items of which each represents a primary part of a principal value and are adapted to be denoted selectively by one of said indicating sections according to the rotated position of said members; a second rotatable member provided with indicia, individual items of which each represents the secondary part of a principal value and are adapted to be denoted selectively by the other of said indicating sections according to the rotated position of said second member; a sleeve carried by said support and having end portions protruding oppositely from said support to provide axially spaced bearing portions on which said members are journaled respectively with their inner ends in face-to-face relationship; a first operating knob secured to the outer end of one of said members and having an axial opening coaxial with said sleeve; a rod secured to the outer end of the other of said members and extending through said sleeve and into said open-

ing; a second operating knob secured to said rod and being located adjacent said first operating knob, there being positive clearance between the group of parts including said first operating knob and the associated rotatable member and the group of parts comprising said second operating device, said rod, and the associated rotatable member, and means cooperating with the respective indicating sections of said shield to facilitate the collective relating of selected markings on the two cooperating members.

4. In a percentage computation aid apparatus, a shield comprising two adjacent indicating sections, each section being marked with a series of progressively varying percent rates and having a principal value designation part and a series of individual view openings aligned respectively with the percent rate markings, said openings being in step arrangement, the percent rate markings on said two sections being the same as to values and progression and the step arrangement of the view openings in said two sections being similar; guide lines on said shield extending respectively between and denoting two view openings in the respective sections aligned with equal percent rate markings; a first member mounted to move behind one of said indicating sections and being marked with a column of primary principal values adapted to register with the principal value designation part of said one of said indicating sections, and being also marked with columns of primary percentages of said primary principal values adapted to be displayed through the openings aligned with the percent rate markings on said one of said shield sections; and a second member mounted to move behind the other of said indicating sections and being marked with a column of secondary principal values and being also marked with columns of secondary percentages of said secondary principal values adapted to be displayed through the openings aligned with the percent rate markings on said other of said indicating sections.

5. In a percentage computation aid apparatus, a shield comprising two adjacent indicating sections, each section being marked with a series of aligned progressively varying percent rates and having a principal value designation part and a series of individual view openings aligned respectively with the percent rate markings transversely to the alignment of the markings of said series, said openings being in step arrangement and at progressively varying distances from the percent rate markings with which they are respectively aligned, the percent rate markings on said two sections being the same as to values and progression and the step arrangement of the view openings in said two sections being similar; guide lines on said shield extending respectively between and denoting two view openings in the respective sections aligned with equal percent rate markings; a first member mounted to move behind one of said indicating sections and being marked with a column of primary principal values adapted to register with the principal value designation part of said one of said indicating sections, and being also marked with columns of primary percentages of said primary principal values adapted to be displayed through the openings aligned with the percent rate markings on said one of said shield sections; and a second member mounted to move behind the other of said indicating sections and being marked with a column of secondary principal values and being also marked with columns of secondary per-

centages of said secondary principal values adapted to be displayed through the openings aligned with the percent rate markings on said other of said indicating sections, all of said 5 columns extending transversely to said series of aligned percent rates.

6. In a percentage computation aid apparatus, a shield comprising two adjacent indicating sections, each section being marked with a series of 10 progressively varying percent rates and having a principal value designation part and a series of individual view openings aligned respectively with the percent rate markings, said openings being in step arrangement, the percent rate markings on 15 said two sections being the same as to values and progression and the step arrangement of the view openings in said two sections being similar; guide lines on said shield extending respectively between and denoting two view openings in the 20 respective sections aligned with equal percent rate markings; a first cylinder mounted to rotate behind one of said indicating sections and being marked with a circumferential column of primary principal values adapted to register with the principal value designation part of said one of said indicating sections, and being also marked with circumferential columns of primary percentages of said primary principal values adapted to be displayed through the openings aligned with the 25 percent rate markings on said one of said shield sections; and a second cylinder mounted coaxially with said first cylinder to rotate independently of said first cylinder and behind the other of said indicating sections and being marked with a circumferential column of secondary principal values and being also marked with circumferential columns of secondary percentages of said secondary principal values adapted to be displayed through the openings aligned with the 30 percent rate markings on said other of said indicating sections.

7. In a percentage computation aid apparatus, a cylinder provided with a circumferential column of principal value markings; a series of separate 45 annular sleeves mounted coaxially on said cylinder in end to end relation and being respectively marked with percentages, said annular sleeves being mountable on and demountable from said cylinder by movement axially of the cylinder; and cooperating means on the cylinder and sleeves respectively for maintaining said sleeves in predetermined position circumferentially with respect to said cylinder.

8. In a percentage computation aid apparatus, 55 a cylinder provided with a circumferential column of principal value markings; a series of separate annular sleeves mounted on said cylinder and being respectively marked with percentages, said annular sleeves being mountable on and demountable from said cylinder by movement axially of the cylinder; and inter-engaging corrugations in the cylinder and sleeves respectively for maintaining said sleeves in predetermined position circumferentially with respect to said cylinder.

9. In a percentage computation aid apparatus, a fixed shield comprising two adjacent indicating sections each marked with a series of progressively 60 varying percent rates and having a principal value designation part and a series of view openings aligned respectively with the percent rate markings, said openings being in step arrangement, the percent rate markings on said two sections being the same as to values and progression and the step arrangement of the view openings 70 in said two sections being similar; a first mem-

ber mounted to move behind one of said indicating sections and being marked with a column of primary principal values adapted to register with the principal value designation part of said one of said indicating sections, and being also marked with columns of primary percentages of said primary principal values adapted to be displayed through the openings aligned with the percent rate markings on said one of said shield sections; a second member mounted to move behind the other of said indicating sections and being marked with a column of secondary principal values and being also marked with columns of secondary percentages of said secondary principal values adapted to be displayed through the openings aligned with the percent rate markings on said other of said indicating sections; and a screen mounted in front of said movable members to move in the same general direction as said movable members move, said screen having slot means extending transversely to said columns and being adapted to register simultaneously with two selected view openings in the respective indicating sections aligned with equal percent rate markings, the non-slotted portion of said screen cutting off the view through the open openings of the percentage value columns behind said other openings.

10. In a percentage computation aid apparatus, a fixed shield comprising two adjacent indicating sections each marked with a series of aligned progressively varying percent rates and having a principal value designation part and a series of view openings aligned respectively with the percent rate markings transversely to the alignment of the markings of said series, said openings being in step arrangement and at progressively varying distances from the percent rate markings with which they are respectively aligned, the percent rate markings on said two sections being the same as to values and progression and the step arrangement of the view openings in said two sections being similar; a first member mounted to move behind one of said indicating sections and being marked with a column of primary principal values adapted to register with the principal value designation part of said one of said indicating sections, and being also marked with columns of primary percentages of said primary principal values adapted to be displayed through the openings aligned with the percent rate markings on said one of said shield sections; a second member mounted to move behind the other of said indicating sections and being marked with a column of secondary principal values and being also marked with columns of secondary percentages of said secondary principal values adapted to be displayed through the openings aligned with the percent rate markings on said other of said indicating sections; and a screen mounted in front of said movable members to move in the same general direction as said movable members move, said screen having slot means extending transversely to said columns and being adapted to register simultaneously with two selected view openings in the respective indicating sections aligned with equal percent rate markings, the non-slotted portion of said screen cutting off the view through the other openings of the percentage value columns behind said other openings, all of said columns extending transversely to said series of aligned percent rates.

11. In a percentage computation aid apparatus, a fixed shield comprising two adjacent indicat-

ing sections each marked with a series of progressively varying percent rates and having a principal value designation part and a series of view openings aligned respectively with the percent rate markings, said openings being in step arrangement, the percent rate markings on said two sections being the same as to values and progression and the step arrangement of the view openings in said two sections being similar; a first cylinder mounted to rotate behind one of said indicating sections and being marked with a circumferential column of primary principal values adapted to register with the principal value designation part of said one of said indicating sections, and being also marked with circumferential columns of primary percentages of said primary principal values adapted to be displayed through the openings aligned with the percent rate markings on said one of said shield sections; a second cylinder mounted coaxially with said first cylinder to rotate independently of said first cylinder and behind the other of said indicating sections and being marked with a circumferential column of secondary principal values and being also marked with circumferential columns of secondary percentages of said secondary principal values adapted to be displayed through the openings aligned with the percent rate markings on said other of said indicating sections; and a screen mounted in front of said cylinders to move in the same general direction as said cylinders move, said screen having slot means extending transversely to said columns and being adapted to register simultaneously with two selected view openings in the respective indicating sections aligned with equal percent rate markings, the non-slotted portion of said screen cutting off the view through the other openings of the percentage value columns behind said other openings.

12. In a percentage computation aid apparatus, a centrally disposed support; a transverse mounting member carried by said support and protruding therefrom to form oppositely disposed, coaxial bearing members; a primary principal value and percentage computation unit rotatably mounted on one of said bearing members; a secondary principal value and percentage computation unit rotatably mounted on the opposite bearing member, independently of said first unit; each of said units comprising a cylinder, marked with a circumferential column to represent parts of principal values and adapted to be combined with markings of the corresponding columns of the opposite unit to collectively constitute selected principal values, and a series of circumferential columns representing percentages of the respective parts of the principal values and adapted to be combined with corresponding columns of the opposite unit to collectively constitute complete percentages of selected principal values; a common shield carried by said support and overlying adjacent portions of the peripheries of said units; said shield comprising two adjacent indicating sections, each marked with a series of aligned progressively varying percentage rates and having a principal value designation part and a series of individual view openings aligned respectively with the percentage rate markings transversely to the alignment of the markings of series, said openings being in step arrangement and at progressively varying distances from the percentage rate markings with which they are respectively aligned; and guide lines on said shield extending respectively between and de-

noting two view openings in the respective sections aligned with equal percentage rate markings to facilitate the collective relating of markings of the two cooperating units.

13. In a percentage computation aid apparatus, a fixed shield comprising two adjacent indicating sections each marked with a series of progressively varying percent rates and having a principal value designation part and a series of view openings aligned respectively with the percent rate markings, said openings being in step arrangement, the percent rate markings on said two sections being the same as to values and progression and the step arrangement of the view openings in said two sections being similar; a 15 first member mounted to move behind one of said indicating sections and being marked with a column of primary principal values adapted to register with the principal value designation part of said one of said indicating sections, and being 20 also marked with columns of primary percentages of said primary principal values adapted to be displayed through the openings aligned with the percent rate markings on said one of said shield sections; a second member mounted 25 to move behind the other of said indicating sections and being marked with a column of secondary principal values and being also marked with columns of secondary percentages of said secondary principal values adapted to be displayed through the openings aligned with the percent rate markings on said other of said indicating sections; a screen mounted in front of said 30

movable members to move in the same general direction as said movable members move, said screen having slot means extending transversely to said columns and being adapted to register simultaneously with two selected view openings in the respective indicating sections aligned with equal percent rate markings, the non-slotted portion of said screen cutting off the view through the open openings of the percentage value columns behind said other openings, a peripheral slot in said shield, and a radially projecting button on said screen, extending through said slot for manipulating said screen.
